UNITED STATES PATENT OFFICE

118,374

DESIGN FOR A GARBAGE RECEPTACLE

Meyer Kamenstein, New York, N. Y.

Application July 9, 1938, Serial No. 78,370

Term of patent 7 years

To all whom it may concern:

Be it known that I, Meyer Kamenstein, a citizen of the United States and a resident of the city, county, and State of New York, have invented a new, original, and ornamental Design for a Garbage Receptacle, of which the following is a specification, reference being had to the accompanying drawing, forming a part thereof.

The figure is a perspective view of a garbage receptacle showing my new design.

The design is characterized by a receptacle of the form shown, the cover thereof being substantially dome-like in contour, and having a

frusto-conical beveled portion intermediate the top of the dome and an angular flange forming the rim of the cover, the apex of the dome portion being provided with a beveled knot of a color contrasting with the surface finish of the cover, all as illustrated, the body of the receptacle being provided with a stripe at the base portion of a color contrasting with the body thereof.

I claim:

The ornamental design for a garbage receptacle, as shown and described.

MEYER KAMENSTEIN.
